UNITED STATES PATENT OFFICE.

GARY B. SMITH, OF CHICAGO, ILLINOIS; HATTIE C. SMITH ADMINISTRATRIX OF SAID
GARY B. SMITH, DECEASED.

WIRE AND CROSSTIE LINK ASSEMBLING MACHINE.

Application filed May 9, 1923. Serial No. 637,783.

To all whom it may concern:

Be it known that I, GARY B. SMITH, a citizen of United States, residing at Chicago, in the county of Cook and State of Illinois, 5 have invented certain new and useful Improvements in a Wire and Crosstie Link Assembling Machine, of which the following is a specification, reference being had therein to the accompanying drawing.

10 The present invention is a machine for applying cross tie links to a cable of twisted wire or similar member from which bed fabrics and the like are made, and it is the primary object of the invention to provide a 15 novel and improved machine of that kind, which will operate in a practical and efficient manner.

As a further object, the invention aims to 20 provide such a machine which is improved generally in its construction and details, to enhance the utility and efficiency thereof.

Another object is the provision of means 25 for bending portions of the cross tie links into hooks embracing the twisted wire or other similar member and for closing said hooks on such member to securely fasten the cross tie links thereto one at a time in succession at longitudinally spaced points of said wire or member.

30 The machine is also designed to bend the terminals of doubled looped cross tie links on the wire or similar member, and for spreading or separating the intermediate portions of the cross tie links.

35 A still further object is the provision of novel means for guiding and supporting the twisted wire or similar member for the application of the cross tie links thereto.

Another object is the provision of novel 40 means for feeding or advancing the twisted wire or similar member as the cross tie links are applied thereto.

A further object is the provision of an 45 automatic cutter device to cut the finished product, or the wire with the cross tie links thereon, into predetermined lengths.

With the foregoing and other objects in view, which will be apparent as the description proceeds, the invention resides in the 50 construction and arrangement of parts, as hereinafter described and claimed, it being understood that changes can be made within the scope of what is claimed, without departing from the spirit of the invention.

The invention is illustrated in the accompanying drawing, wherein—

Figure 1 is a plan view of the machine.

Fig. 2 is a detail plan view of the bending devices and corresponding parts, portions being shown in section.

Fig. 3 is an enlarged cross-section on the line 3—3 of Fig. 1.

Fig. 4 is an enlarged vertical section on the line 4—4 of Fig. 1.

Fig. 5 is an enlarged elevation of the cutter device.

Fig. 6 is an enlarged elevation of the cross tie link bending devices.

Fig. 7 is a horizontal section on the line 7—7 of Fig. 6.

Fig. 8 is a perspective view of the hook bending and anvil member.

Fig. 9 is a view corresponding with Fig. 6, showing a modification.

The present machine is substantially the same, in general respects, with the machine or mechanism as disclosed in my Patent No. 1,116,506, granted November 10, 1914, with such changes and improvements as herein-after described. The machine has the drive 50 shaft 20 driven by a sprocket chain 21 or other means, and the twisted wire 25 is fed or delivered from a wire twisting machine, reel or other source to pass through the machine for the application of the cross tie 55 links thereto.

The machine has a reciprocatory feeder or advancer 30 for intermittently feeding or advancing the wire 31 from which the cross tie links are fashioned, substantially the same as disclosed in Patent No. 1,116,506, and the forward terminal of the wire, when doubled, is fed or advanced forward by the feeder or advancer 30 over the hook bending 60 and anvil member 33 and a loop bending member 36. The cross tie link 34 of doubled wire is of loop form, and the terminals of the wire are bent back into hooks 35 at the end of the cross tie link opposite to the bend or loop, and with the present machine, the hooks 35 of the cross tie links are made to embrace the wire 25. The production of the cross tie links by the machine is substantially the same as disclosed in said patent, but in applying the cross tie links to the 65 wire 25, provisions are made to accomplish the desired results.

The machine includes a tubular rock

shaft 37 journaled in the frame 42 and carrying the hook bending member 33 at the end thereof from which the wire 25 passes, and the loop bending member 36 is 5 carried by the corresponding end of a tubular shaft 38 journaled in the frame parallel with the shaft 37. The shafts 37 and 38 have the gear wheels 39 and 40 thereon, respectively, meshing with one another so 10 that said shafts turn simultaneously in opposite directions, the gear wheel 40 being of larger diameter than the gear wheel 39 so as to turn the shaft 38 and member 36 through a smaller angle than the shaft 37 and member 33 accordingly. The machine has a 15 rack 41 reciprocated from the drive shaft 20 and meshing with the gear wheel 39 for oscillating the shafts 37 and 38 in proper timed relation, and the wire feeder or ad- 20 vancer 30 is also reciprocated from the shaft 20.

In running the wire 25 through the machine, a tube 43 is fitted within the tubular rock shaft 37 and extends from the member 25 33 beyond the opposite end of the shaft 37 to be secured rigidly to the frame 42, so that the tube 43 remains stationary, while the shaft 37 rotates around said tube. The tube 43 has fitted therein a reciprocatory 30 guide tube 45 through which the wire 25 passes, and that end of the tube 45 adjacent to the member 33 has a reduced extension 46 to project out over the member 33 and to provide a substantial element around which 35 the hooks 35 of the cross tie links can be bent, as will hereinafter more fully appear. A screw or member 49 is engaged in the tube 45 near the end thereof opposite to the member 33 and depends through a longitudinal slot 50 in the tube 43, and said screw or member engages a reciprocatory cross 40 head 51 which is slidable on the tube 43. Said cross head is reciprocated in proper timed relation by a lever 52 of the machine 45 which is oscillated from the shaft 20.

A rod 53 is slidable through the shaft 38 to project over the member 36, and projects from the opposite end of the shaft through the cross head 51, and said rod is secured to 50 the cross head by means of a set screw 54. The rod 53 and tube 45 are thus reciprocated as a unit to be projected over and retracted from the bending members 36 and 33, respectively.

A die 55 is mounted for vertical movement above the bending and anvil member 33, being slotted to engage the pins 56 and 57 carried by the frame, and a lever 58 is 55 fulcrumed on the pin 56 and is connected by a link 59 with the die 55, for reciprocating said die. A bar 60 is connected to the upper long arm of the lever 58 and extends past the feeder or advancer 30. Said bar is moved forwardly by a spring 61, so as to 60 swing the lever 58 to the position as shown

in Fig. 6, thereby pulling the link 59 upwardly and raising the die 55. The bar 60 carries a pin 62 projecting behind the feeder 30, so that when said feeder is moved to its rearmost position, the feeder contacts with the pin 62, thereby moving the bar 60 rearwardly and swinging the lever 58 toward a vertical position, and this will shove the link 59 downwardly. Said link and lever provide a toggle connection, whereby the die 55 is forced downwardly with considerable pressure in its lowermost position, the lower end of the die being formed to close and shape the hooks 35 of the cross tie link on the twisted wire. 70

The die 55 also carries a die 63 for spreading or separating the side portions of the cross tie link 34, and the die 63 is slidably connected with the die 55 by the pin and slot connections 64, to permit the dies to move relatively to one another. The die 63 has a wedge 65 projecting downwardly to pass into the link 34 between the members 33 and 36, and said die has shoulders 66 to seat on the side portions of the link when the wedge has been forced down into the link. A spring 68 is confined between the die 63 and lug 67 on the die 55, for yieldingly depressing the wedge 65 relatively to the die 55. 80

The twisted wire 25 is fed or advanced through the tube 45 step by step in synchronism with the feeding or advancing of the wire 31. Thus, a slide 70 is mounted for reciprocation in a bracket or guide 71 of the frame 42, for movement toward and away from the tube 45, and the slide 70 has a tube 73 projecting forwardly and telescoping into the tube 45, to prevent the wire 25 buckling between the slide 70 and cross tie link applying means when the wire 25 is moved forwardly. A wire gripping lever 74 is pivoted in the slide 70 and has a toothed jaw 75 to bite the wire 25 which passes through the slide 70 and tube 73. 90

The slide 70 is operated simultaneously with the wire feeder 30 so that the twisted wire 25 and cross tie wire 31 are both advanced at the same time. Thus, the lever 74 is connected by a link 76 with a bell crank lever 77 fulcrumed on the frame, and said lever is connected by a link 78 with the feeder 30. Therefore, when the feeder 30 is advanced, the link 78 swings the lever 77 so that the link 76 is pulled forwardly to advance the slide 70, and the pull on the link 76 will swing the lever 74 to grip the wire 25, thereby advancing it with the slide 70. When the feeder 30 returns, the slide 70 is moved rearwardly, the lever 74 being swung to release the wire 25 during the return movement of said slide. The joint 79 between the link 76 and lever 77 is preferably adjustable so as to regulate the amount of movement of the slide 70, in order that the 100

105

110

115

120

125

130

twisted wire 25 is advanced the desired distance for the proper longitudinal spacing of the cross tie links on the twisted wire.

A wire cutting device is provided for automatically cutting the wire 25 into any desired lengths within the limits of adjustment of the device, thereby relieving the operator of this duty, and assuring of accurate cutting of the wire without the attention of the operator. The frame 42 has a ledge or surface 80 over which the twisted wire 25 passes with the cross tie links thereon, and a wheel 81, which serves both as a ratchet wheel and cutter, is mounted for rotation on a stud 82 carried by the frame. This ratchet wheel 81 has an annular series of slots or notches 83 to register in succession with the ledge 80 for the passage of the wire 25 and cross tie links, and when the ratchet wheel is rotated one step it will shear or sever the wire between the respective cutting edge of the wheel 81 and the cutting edge of the ledge 80, and the next slot 83 is brought into registration with the ledge 80.

The ratchet and cutter wheel 81 is rotated step by step, and the actuating means is adjustable to advance the ratchet wheel one step for a given adjustment, so that the desired length of wire will pass through before being cut. The actuating means includes an arm 84 mounted for rocking movement on the stud 82 and carrying a pawl 85 engaging the ratchet teeth of the wheel 81, and a retractile spring 86 is connected to the arm 84 whereby to return the arm 84 so as to advance the ratchet wheel one step. A spring buffer 87 is carried by the frame to stop the arm 84 and cushion same. The arm 84 is moved against the tension of the spring 86 by means of a ratchet wheel 88 mounted on a stud 89 carried by the frame, and said wheel 88 has a roller pin 90 to contact with and wipe along the arm 84 which extends partially across the face of the wheel 88. Thus, as the wheel 88 rotates, the pin 90 will swing the arm 84 away from the buffer 87 and the arm is then released so that the spring 86 comes into play for returning said arm. The pawl 85 during such return of the arm will advance the ratchet wheel 81 one step so as to cut the wire 25 and bring the next slot 83 into registration with the ledge 80, so that the wire can pass from the machine. An arm 91 mounted on the stud 89 is connected by a connecting rod or link 92 with a radially adjustable wrist pin 93 carried by a slide 94 movable in a diametrical slot in a crank disk 95 secured on a shaft 96 driven by the machine, said slide 94 being adjusted by a screw 97. Thus, the wrist pin 93 can be adjusted to regulate the throw of the connecting rod 92 and arm 91, and the smaller the throw, the greater number of rotations of the shaft 96 there will be necessary to actuate the cutting device. The

arm 91 carries a plurality of pawls 98 engaging the ratchet teeth of the wheel 88, and so arranged as to avoid lost motion when the arm 91 is swung to advance the wheel 88. A set of pawls 99 carried by the frame prevents reverse movement of the wheel 88. The pawls 98 and 99 are so spaced with respect to the ratchet teeth as to have the same effect as if the ratchet teeth were of considerably shorter length. Thus, with three pawls 75 on the arm 91, one of them will engage the shoulder of a ratchet tooth before the arm 91 moves a distance greater than one third the length of a ratchet tooth, and by using a greater number of pawls, the lost motion 80 is reduced proportionately. It therefore requires a predetermined number of revolutions of the shaft 96 to actuate the cutting device. Each time the shaft 96 is rotated once, a predetermined length of twisted wire 85 85 is delivered through the cutting device, and, therefore, after the shaft 96 has rotated a predetermined number of times and delivered a predetermined length of twisted wire with cross tie links thereon, the cutting 90 device is operated automatically to cut the wire. By adjusting the wrist pin 93, the twisted wire can be cut into different lengths, inasmuch as the nearer the wrist pin is to the center of the disk 95, the less will be the 95 throw of the arm 91, and it will require a greater number of revolutions of the shaft 96 accordingly. In fact, by adjusting the wrist pin 93 to its extreme position outwardly from the center of the disk 95, the wire 100 will be cut into short lengths of only a few feet, and in the other extreme, with the wrist pin near the center of the disk 95, the throw of the arm 91 can be reduced to a fraction of one of the teeth of the wheel 88, thereby 105 cutting the wire into lengths of many feet, as high as two or three times the number of teeth of the ratchet wheel 88. During the operation of the machine, the wheel 88 is gradually rotated step by step and the roller 110 pin 90 in moving under the arm 84 will raise it. Then, when the predetermined length of wire has been delivered through the cutting device, the arm 84 is released from the pin 90, thereby advancing the 115 ratchet wheel 81 one step to cut the wire. The wire 25 is cut between the cross tie links, and the cutting device is so adjusted that when the wire 25 has been delivered with a predetermined number of cross tie links 120 thereon, such wire is cut.

The operation of the machine is as follows: When the feeder 30 of the machine advances the wire 31 over the member 33 and onto the member 36, to bring the bend or loop of the wire on the member 36, the slide 70 is also advanced to feed the twisted wire 25 through the tube 45 and over the member 33, the doubled wire 31 passing under the twisted wire 25. The cross head 51 130

is then moved forwardly so as to project the reduced portion 46 of the tube 45 over the member 33 and to project the rod 53 over the member 36, with the doubled wire disposed under the extension or reduced portion 46 and rod 53. The rack 41 is now moved to turn the shafts 31 and 38, and the member 53 is turned clock-wise as seen in Fig. 6, so as to cut the wire 31, the member 33 having a cutting edge 100 movable past a cutting edge 101 on the frame under which the wire 31 passes, thereby severing the cross tie link from the wire. The turning movement of the bending member 33 will also bend the terminals of the wire constituting the cross tie link, and such terminals are bent upwardly over and around the extension or reduced portion 46 and twisted wire 25. The tube 45 provides a rigid portion around which the wire of the cross tie link can be bent by the member 33, without distorting or displacing the wire 25 during the bending of the hooks 35. The bending member 33 has bevelled lugs 102 adjacent to the cutting edge 70 and said lugs have converging faces to force and hold the terminals or hooks 35 of the wire together between the lugs when bending the hooks. The member 36 is rotated in a direction reverse to that of the member 33, thereby bending the loop upwardly at an angle beyond the rod 53, as indicated in dotted lines in Fig. 6. The rack 41 is then retracted, so as to turn the shafts 37 and 38 and members 33 and 36 to normal position, and the cross head 51 is returned to withdraw the tube 45 and rod 53 from over the members 33 and 36. Then, when the feeder 30 returns to its rearmost position it strikes the pin 62, thereby moving the rod 60 rearwardly slightly, and swing the lever 58 to force the die 55 down. This will close the hooks 35 of the cross tie links 34 tightly on the twisted wire 25, and the members 33 will serve as an anvil while the hooks are being crushed or bent down around the twisted wire, the tube 45 having been withdrawn from the hooks 35 so that they can be closed to tightly and frictionally embrace the twisted wire. When the die 55 is moved downwardly, the wedge 65 of the die 63 is forced down into the link 34, thereby separating or spreading the side portions of said link, as seen in Fig. 7, and the shoulders 66 seat on the side portions of the link 34 just before the die 55 bends the hooks 35 down, the die 63 yielding so as to hold the link 34 under pressure on the members 33 and 36, to prevent said link being displaced during the bending of the hooks 35 by the die 55. The member 33 has the lugs or stops 103 on the face thereof between which the terminals of the cross tie link are disposed during the descent of the die 63 to prevent the wedge 65 from spreading or separating the terminals or hooks 35 of the wire. The slide

70 is returned during the return movement of the feeder 30, and when the feeder 30 starts forward to advance the wire 25 for producing the next cross tie link, the rod 60 is moved forwardly by the spring 61, thereby raising the dies 55 and 63, and the twisted wire 25 being advanced one step will carry the cross tie link with it off of the members 33 and 36. The operation is then repeated as before, so as to apply a cross tie link to the twisted wire at predetermined longitudinally spaced points of the twisted wire. 75

The cable or wire turned out by the machine, with the cross tie links thereon, can then be fabricated into bed springs. The automatic cutter device will cut the twisted wire into predetermined lengths, for the convenient working of the lengths of wire into the bed fabric. 80

Fig. 8 illustrates a modification used for applying flat wire and other cross tie links to the twisted wire or cable 25. The member 33 bends one end of the link 34' around the twisted wire 25 to form a hook 35' at one end of the cross tie link, which is closed tightly on the twisted wire by the die 55 when the tube 45 is retracted, and the member 36 bends the other end of the link around the rod 53 to form a hook 35'' at the other or free end of the cross tie link. This arrangement can be used for applying flat wire and other cross tie links to the twisted wire, such links having hooks at both ends. The die 63 is omitted, and the operation is otherwise the same as hereinbefore described, excepting that the member 36 turns through a greater angle to bend the corresponding end of the link into a hook 35''. 90

Having thus described the invention, what is claimed as new is:—

1. A machine of the character described comprising means for advancing wire, a tube through which the wire is advanced, means for supplying cross tie links beyond one end of the tube, a bending member operable at said end of the tube to turn around the wire for bending the cross tie links on the wire, said tube being projected for the bending of the cross tie links around it when they are bent around the wire. 100

2. A machine of the character described comprising means for advancing wire, a tube through which the wire is advanced, means for supplying cross tie links beyond one end of the tube, a bending member operable at said end of the tube to turn around the wire for bending the cross tie links on the wire, said tube being projected for the bending of the cross tie links around it when they are bent around the wire, and means for closing the bent portions of the cross tie links when said tube is retracted. 110

3. A machine of the character described 120

- comprising means for advancing wire, a tube through which the wire is advanced, means for supplying cross tie links one at a time at one end of said tube, and a bending member 5 movable around the wire at said end of the tube for bending the cross tie links into hooks around the wire, said tube being projected for the bending of the cross tie links around the tube.
- 10 4. A machine of the character described comprising means for advancing wire, a tube through which the wire is advanced, means for supplying cross tie links one at a time at one end of said tube, a bending member 15 movable around the wire at said end of the tube for bending the cross tie links into hooks around the wire, said tube being projected for the bending of the cross tie links around the tube, and a die operable to bend the 20 hooks of the cross tie links closed on the wire when said tube is retracted.
5. A machine of the character described comprising means for advancing wire, a member reciprocated to be projected and re- 25 tracted, a bending member mounted for rotary movement, the first named member being projected and the bending member rotated to bend cross tie links around the projected portion of the first named member and wire, and a die operable when said member is retracted and the bending member returned for pressing the bent portions 30 of the links against the bending member to close said bent portions on the wire.
- 35 6. A machine of the character described comprising means for advancing wire, a tubular shaft through which the wire is advanced, means for supplying cross tie links for application to the wire at one end of said shaft, a bending member carried by 40 said end of the shaft to bend the cross tie links around the wire, and means for guiding and supporting the wire for the bending of the cross tie links therearound.
- 45 7. A machine of the character described comprising means for advancing wire, a tube, a tubular shaft rotatable around said tube, means for supplying cross tie links for application to the wire at one end of said tube, a member reciprocated in said tube to 50 be projected and retracted at said end thereof, and a bending member carried by the corresponding end of the shaft for bending the cross tie links around the projected portion of said member and wire.
- 55 8. A machine of the character described comprising means for advancing wire, a tube, a tubular shaft rotatable around said tube, means for supplying cross tie links for 60 application to the wire at one end of said tube, a member reciprocated in said tube to be projected and retracted at said end thereof, a bending member carried by the corresponding end of the shaft for bending the cross tie links around the projected portion of said member and wire.
- 65 9. A machine of the character described comprising means advancing wire, a tube, a tubular shaft rotatable around said tube, means for supplying cross tie links for application to the chain links at one end of said tube, a tube reciprocated in said tube and through which the wire is advanced, and a bending member carried by the corresponding end of the shaft for bending the cross tie links around the second named tube and wire, the second named tube being projected for the bending of the cross tie links therearound and then being retracted. 80
- 70 10. A machine of the character described comprising means for advancing wire, a tube, a tubular shaft rotatable around said tube, means for supplying cross tie links for application to the chain links at one end of said tube, a tube reciprocated in said tube and through which the wire is advanced, a bending member carried by the corresponding end of the shaft for bending the cross tie links around the second named tube and 85 wire, the second named tube being projected for the bending of the cross tie links therearound and then being retracted, and a die for pressing the bent portions of the cross tie links against said bending member when the second named tube is retracted and the bending member returned, to close the bent portions of the cross tie links on the wire. 90
- 95 11. A machine of the character described comprising a member to be projected and retracted, a bending member mounted for turning movement to bend a cross tie link around the projected portion of said member and around wire, and a die for pressing the bent portion of the link closed around the wire against the bending member when the first named member is retracted and the bending member returned. 100
- 105 12. A machine of the character described comprising a tube, cross tie link applying means operable at one end of the tube, a reciprocating slide having a tube through which wire passes, said tubes having a telescopic connection to prevent the wire buckling between said slide and means, and 110 means carried by the slide for gripping the wire to advance it past said means. 115
- 120 In testimony whereof I hereunto affix my signature.

GARY B. SMITH.
